Attorney

UNITED STATES PATENT OFFICE

MARIDA LE DORF, OF LONG BEACH, NEW YORK

FOOT PROTECTOR

Application filed November 6, 1928. Serial No. 317,612.

It is a fashion or practice to wear shoes with no socks or stockings, the flesh of the foot thus coming in contact with the shoe lining. This results in more or less discomfort and may even result in cutting or laceration of the skin or flesh. In accordance with this practice or fashion, no sock or stocking must show above the top edge of the shoe, but the bare leg is exposed. The object of 10 my invention is to permit the following of this fashion which will expose the bare flesh above the top edge of the shoe and at the same time avoid the discomfort and possible danger of injury by contact of flesh or skin 15 with the interior of the shoe. And in particular my object is to accomplish this result by the use of a guard or protector which will have the minimum of bulk both when it is worn and when it is not in use, so that for 20 merchandising purposes or for packing in the bags or luggage of the wearer the minimum of space or room will be required.

My invention consists in whatever is described by or is included within the terms or 25 scope of the appended claims.

In the drawings:

Fig. 1 is a perspective view of a foot protector embodying my invention;

Fig. 2 is a cross-section on the line 2—2 of 30 Fig. 1;

Fig. 3 is a plan view of a blank from which the article is made.

Referring to Fig. 1, it will be seen that the guard or protector is approximately the contour of the sole of the foot, it comprising or being made up of an under or sole portion, 10, and inwardly turned marginal portions, 11, which extend inward from the edge of the sole, 10, on all sides and by the inner edge 35 define or provide a more or less elliptical opening, 12, for the entrance of the foot, so that when on the foot it will overlap and conform to the side and upper surfaces of the foot, but wholly below the marginal edge of the shoe, so that a protecting surface for the 40 foot will be provided at all or substantially all surfaces overlapped by the shoe.

As clearly shown in Figs. 1 and 2, the guard or protector when not on the foot, is 50 substantially flat, the marginal portions 11, lying upon and in contact with the upper side of the sole portion, 10. This, of course, means easy storage in very little space which is important for merchandising purposes and for carrying or transportation as in hand 55 bags.

The flat or substantially flat form of the completed article is due to the shape or contour of the blank from which it is made. This is clearly shown in Fig. 3, the blank 60 comprising a longitudinally extending central portion, 100, which provides the sole, 10, the heel end being a fairly flat curve, 13, and the toe end a somewhat pointed curve, 14, and at each side a longitudinally extending side 65 or wing portion, 110, which transversely is one half the width of the sole blank, 100, and at heel and toe ends each side portion is shaped symmetrically with the heel and toe ends of the sole portion, so that when a side 70 or wing portion of the blank is turned over on the longitudinal line, 15, the appearance of the finished article in Fig. 1 will result when the overlapping end edges are sewed together or joined along the curves, 13 and 75 14. The meeting edges, 16, of the wings, 110, at the toe are jointed by a line of stitching, 17, and the meeting edges at the heel are jointed by a line of stitching, 18, each extending inward respectively, to the front and rear 80 end of the opening, 12.

Any suitable, thin, light, soft material may be used as for example textile fabrics of silk, wool, cotton or combinations thereof.

What I claim is:

1. An article of foot wear comprising a sole portion and marginal portions extending inwardly from the edges of the sole portion and flatwise and unattached at a portion of their inner edges to provide an opening for inserting the foot, the sole and marginal portions being stitched at heel and toe, and portions of the opposite edges of the marginal portions at heel and toe being joined by lines of stitching that reach to the ends of the foot 95 opening.

2. An article of footwear comprising a flat sole portion and marginal portions extending inwardly from the edges of the sole portion and lying directly upon and parallel with the 100

upper flat surface of the sole portion and reaching inward flatwise over the sole portion from the heel entirely around the sole portion and lying wholly within the normal 5 contour of the sole portion, said marginal portions being unattached at their inner edges to provide an opening for inserting the foot, opposite edges of the marginal portions at heel and toe being joined by a seam that 10 reaches inwardly from the sole edge at heel and toe respectively, said marginal portion being flexible to permit the thrusting of the foot between the same and the sole portion, said marginal portions when the article is on 15 the foot extending a substantial distance upward over the foot entirely around the foot from heel to toe.

3. An article of footwear comprising a sole portion having a contour which includes heel 20 and toe portions in a continuous piece and marginal portions extending inwardly from the edges of the sole portion in a continuous piece and normally lying flatwise upon the upper surface of the sole portion, said marginal portions being unattached at their inner 25 edges to provide an opening for inserting the foot and which edges when the article is on the foot extend continuously around the adjacent portion of the foot, the sole and marginal portions being of flexible, thin, soft 30 textile fabric and opposite edges of the marginal portions being joined by a seam at the heel that reaches inwardly from the sole edge.

In testimony whereof I hereunto affix my
35 signature.
